M. A. REPLOGLE,
METHOD AND APPARATUS FOR TREATING SELVAGE,
APPLICATION FILED JULY 12, 1919.

Patented Apr. 19, 1921.

UNITED STATES PATENT OFFICE.

MARK A. REPLOGLE, OF AKRON, OHIO, ASSIGNOR TO THE GOODYEAR TIRE & RUBBER COMPANY, OF AKRON, OHIO, A CORPORATION OF OHIO.

METHOD AND APPARATUS FOR TREATING SELVAGE.

1,375,468.

Specification of Letters Patent. Patented Apr. 19, 1921.

Application filed July 12, 1919. Serial No. 310,347.

To all whom it may concern:

Be it known that I, MARK A. REPLOGLE, a citizen of the United States, residing at Akron, in the county of Summit and State 5 of Ohio, have invented new and useful Improvements in Methods and Apparatus for Treating Selvage, of which the following is a specification.

My invention relates to a method of treating 10 selvage of fabric in order to render it of such a character that it may be suitably calendered and manipulated, and to an apparatus for practising the aforesaid method.

In weaving fabric to be utilized in various 15 industries it has been customary to weave the edge in such a manner that the unraveling thereof will be prevented. In some industries, notably that of pneumatic tire manufacture, it is necessary to calender 20 the fabric, that is to say, to incorporate with it a rubber compound, and it has been found that the usual selvage edge is not well adapted to take up this compound, since the fibers at the edge are not loose and pliable, but on 25 the contrary are bound together and more or less unflexible, and consequently the calendering material cannot be readily worked into the same. But even if the selvage could be properly calendered, it would still be 30 thick and not readily workable to shape the fabric about the body.

Hitherto the practice has been to trim off this selvage, either by hand or by mechanical trimming mechanism; and to discard 35 the trimmings, resulting in a considerable waste of material.

It is primarily the object of my invention to provide a method for treating selvage which shall avoid all wastage, and at the 40 same time more suitably prepare the fabric at the selvage for calendering, and for subsequently applying the fabric.

It is a further object of my invention to provide an apparatus which is adapted to 45 pound, beat, or strike the fabric selvage uniformly in such a way as to bruise, break, loosen and elongate the fibers, so that they may more readily be incorporated with the calendering material and when so incorporated may be readily manipulated to be pressed into place.

A still further object of my invention is to

provide means for determining the distance between the striking surface and that of the support for the material, whereby fabric of 55 different thicknesses may be accommodated and uniformly treated.

More particularly, my method consists in treating the selvage by beating it to flatten it out and loosen the fibers therein, 60 and is one which may be uniformly, efficiently and economically practised by means of an apparatus, an embodiment whereof is herein illustrated and which also constitutes a part of my invention.

While my method and the apparatus for practising it may be broadly applied for the treatment of any fabric having a selvage, I have found that they are particularly useful in treating the selvage of fabric to be calendered with a rubber compound 70 for the manufacture of articles such as pneumatic tires and the like.

It is to be understood that my invention 75 is not to be regarded as limited to any particular industry, however, nor the scope and extent thereof to any specific apparatus for practising the method herein disclosed, except as defined by the claims, hereto appended and forming a part of this application.

The following description when considered with reference to the accompanying drawings, wherein I have illustrated one form of an apparatus wherewith my invention 85 may be practised, will afford an understanding of both the method and an apparatus for carrying it out.

With reference to the drawings, wherein there has been illustrated a preferred embodiment of the invention, and throughout the several views of which similar reference numbers designate corresponding parts:

Figure 1 is a plan view of an apparatus 90 for practising my method, the apparatus being shown as applied to both edges of a strip of fabric;

Fig. 2 is a side elevation of one end of the apparatus shown in Fig. 1;

Fig. 3 is a perspective view of the apparatus;

Figs. 4 and 5 are detail views showing an element of the apparatus in vertical section;

Fig. 6 is an elevation of the apparatus

with which a modified form of support for the fabric edge and adjustment therefor has been incorporated; and

Fig. 7 is a perspective view of the adjustable support shown in Fig. 6.

A strip of fabric 10 is caused to travel across a stationary mandrel 11, which is usually cylindrical in form, and rests in troughs 12, which are secured by any desired means, 10 such as bolts, to a supporting bed 13. The mandrel should preferably be of a length approximately the same as the width of the fabric, the selvage of which is being treated, and the means disclosed for supporting the 15 mandrel, permits its ready replacement by a mandrel of the desired length and diameter. Thus by using a mandrel of greater diameter, a thinner fabric will be given the same degree of treatment as a thick one, 20 with a mandrel of lesser diameter.

Base members 14 are secured to the bed 13 at the outer ends thereof, each of said base members 14 being provided with an offset dove-tail 15, which is adapted to fit with 25 sliding engagement into a corresponding dove-tail groove 16 in a base 17 to which a motor 18 is bolted.

A hand screw 19 is supported by an up-standing bracket 20, secured to or forming 30 an integral part of the base member 14. One end of said hand screw 19 is provided with hand wheel 21 for operating the screw, while the other end of the screw is swiveled in base 17, thus permitting the adjustment 35 of the motor toward and away from the edge of the fabric, so that the apparatus may accommodate varying widths of fabric.

A guiding flange 22 is also bolted to the motor base 17 and is consequently moved 40 with the motor and base. This flange 22 is provided with fingers 22^a adapted to overlie the fabric as seen in Figs. 1 and 2.

The motor 18 is provided with the usual shaft 23, and to the shaft is keyed a substantially rectangular head 24. This head comprises side pieces 25, connected by a pair of studs 26, passing through the ends of said side pieces 25, the studs 26 being provided with shoulders 27, to hold the side pieces 25 properly spaced. Wheels or disks 28 having preferably beveled or curved edges are loosely mounted on the studs 26, which serve as axles therefor, by being provided with central holes 28^a, which are appreciably larger than the studs 26, and through 55 which the studs pass. Instead of wheels or disks 28, it is obvious that other elements having a different form, might be used, for example, spherical bodies.

60 While I have described but one apparatus, it will be understood that the apparatus is really in duplicate, one being located at each side of the fabric strip as clearly shown in Figs. 1 and 2.

65 From the above description of the appara-

tus, its operation and the method performed thereby will be readily apparent.

A strip of fabric is caused to pass over the mandrel 11, which just comes to the edges of the fabric. The motors 18 are adjusted by means of the hand wheels 21 so that the wheels 28 will engage the selvage or edge of the fabric material.

Upon operation of the motor 18 the head 24 will be rapidly rotated, and the wheels 28 will strike the selvage with successive blows of great frequency. It will be understood that for efficient operation the diameter of the mandrel should be selected such that the selvage will be pounded with the proper degree of force, such action being permitted by the loose mounting of the wheels 28. The speed of travel of the fabric should also be so regulated that substantially the same surface of the selvage may be struck several times, so as to thoroughly bruise, break and loosen the fibers therein.

Referring now to Figs. 6 and 7, instead of having the mandrel 11 extend to the edge of the fabric, a shorter mandrel may be used, and at the end thereof, directly below the shaft 23 of the head 24, is arranged an anvil 30, which serves as the striking surface over which the fabric selvage passes. The anvil 30 passes up through an aperture 31 in a block 32, and is provided on its lower surface with a cam face 33, which abuts against a similar surface 34 of a wedge 35, so that the anvil 30 rests on the wedge. The wedge 35 is provided at its outer end with a depending lug 36, having a slot for receiving the end of a hand-screw 37, suitably supported in a bracket 38 upstanding from the base of the block 32, as seen in Fig. 7. The wedge 35, by its adjustment forward or backward, by manipulation of the hand-screw 37, thus raises and lowers the anvil 30, so that fabrics of different thicknesses may be treated. A set screw 40 may be used to firmly hold the anvil 30 in place, and the anvil support is suitably secured, as by bolts 41, to the bed 13.

Thus it will be seen that my method of treating selvage consists in pounding, striking or beating the selvage so as to break, 115 loosen and elongate or flatten out the fibers therein, to prepare them for calendering and other manipulation, and while I have shown one type of apparatus suitable for practising the method, it will be understood that 120 I do not mean to be limited to an apparatus of the type shown, for it is readily apparent that not only may the method be carried out by hand, though not with the same degree of efficiency, as by pounding and bruising the selvage with a hammer, but it may be practised with numerous other forms of apparatus, which are easily conceivable, such as a machine that will apply a continuous series of successive blows by some 130

rapidly reciprocating element, for example a trip hammer used for riveting, or by a rotating element provided with members which are thrown out centrifugally to strike the selvage as the element rotates.

5 Although certain reasons or theories have been advanced as to the purposes and advantages of my method, it is to be understood that I do not desire to impose thereby 10 any limitations to the scope of the appended claims.

What I claim is:

1. A method of treating selvage which 15 consists in pounding the selvage with forcible blows to bruise, loosen and elongate the fibers therein.

2. A method of treating fabric selvage 20 which consists in moving the fabric in the direction of its length, subjecting the selvage thereof to a series of rebounding blows delivered obliquely with respect thereto, and supporting the selvage against the impact of the blows.

3. A method of treating fabric selvage 25 which consists in moving the fabric in the direction of its length, subjecting the selvage thereof to a series of rebounding blows delivered obliquely with respect thereto, and rigidly supporting the selvage against the impact of the blows.

4. A method of treating fabric selvage 35 which consists in moving the fabric in the direction of its length, subjecting the selvage thereof to a series of blows delivered obliquely with respect thereto and in the direction of its length, and rigidly supporting the selvage against the impact of the blows.

5. A method of treating fabric selvage 40 which consists in moving the fabric, subjecting the selvage thereof to a series of blows delivered in the direction of the movement of the fabric, and rigidly supporting the selvage against the impact of the blows.

45 6. A method of treating fabric selvage which consists in moving the fabric, subjecting the selvage thereof to a series of rebounding blows delivered in the direction of the movement of the fabric, and rigidly supporting the selvage against the impact of the blows.

7. A method of treating fabric selvage 55 which consists in subjecting the selvage to a series of rebounding blows delivered obliquely with respect thereto and at intervals of the length thereof, and rigidly supporting the selvage under the impact of the blows.

8. A method of treating fabric selvage 60 which consists in moving the fabric in the direction of its length, subjecting the selvage thereof to a series of rebounding blows delivered obliquely with respect thereto, and supporting and guiding the selvage under the impact of the blows.

9. An apparatus for treating selvage comprising means for beating the selvage with blows delivered in the direction of its length to break, loosen and elongate the fibers therein, and means for rigidly supporting the selvage at the zone of the beating operation.

10. An apparatus for treating selvage comprising means for beating the selvage with blows delivered in the direction of its 75 length to break, loosen and elongate the fibers therein, means for feeding the selvage beneath the first means, and means for supporting the selvage at the zone of the beating operation.

80 11. An apparatus for treating selvage comprising means for applying to the selvage rebounding blows to break, loosen, and elongate the fibers therein.

12. An apparatus for treating selvage 85 comprising power operated means for pounding the selvage with rebounding blows to bruise, loosen, and elongate the fibers therein, means for feeding the selvage, and adjustable means for supporting 90 the selvage at the zone of the pounding operation.

13. An apparatus for treating selvage comprising power operated means for beating the selvage to bruise, loosen and elongate the fibers therein, said means comprising devices constructed to deliver a series of rebounding blows in the direction of the length of the selvage, means for feeding the selvage to said first means, and adjustable 100 means for rigidly supporting the selvage 95 against the impact of the blows.

14. A device for treating selvage, comprising eccentrically mounted beater elements having a concentric axis of revolution.

105 15. A device for treating selvage comprising eccentrically mounted revoluble beater elements having a concentric axis of revolution.

16. A device for treating selvage comprising eccentrically mounted revoluble beater elements having a concentric axis of revolution and constructed to rebound upon their respective eccentric mountings.

115 17. An apparatus for treating selvage comprising a support over which fabric having a selvage is adapted to pass, power operated means for applying a series of regularly intermittent blows to the selvage 120 as it passes over the support.

18. An apparatus for treating selvage comprising a power driven rotatable shaft, means adapted to be secured to said shaft, comprising an element carrying a plurality of loosely mounted members, adapted upon rotation of said shaft and element, to intermittently strike the selvage of a supported fabric strip.

125 19. A device for treating selvage and 130

- adapted to be secured for rotation to a power driven shaft, comprising a plurality of wheels loosely mounted and eccentric to the axis of said device.
- 5 20. A device for treating selvage and adapted to be secured for rotation to a power driven shaft, comprising spaced side pieces, wheels loosely mounted between said side pieces, said wheels being adapted, on 10 rotation of said device, to strike the selvage of fabric supported beneath the same.
- 15 21. An apparatus for treating selvage comprising a motor having a shaft, an adjustable supporting base for said motor, means for supporting a strip of fabric adjacent said motor, a head carried by said motor shaft, said head including a plurality of spaced elements, and a plurality of members loosely supported by said elements, 20 and means whereby the adjustment of said base may be effected to cause said members to intermittently strike the selvage of said fabric upon rotation of said shaft and head.
22. An apparatus for treating selvage 25 comprising an adjustable support over
- which fabric having a selvage is adapted to pass, power operated means for applying a series of regularly intermittent blows to the selvage as it passes over the support.
23. An apparatus for treating selvage 30 comprising a motor having a shaft, an adjustable supporting base for said motor, adjustable means for supporting a strip of fabric adjacent said motor, a head carried by said motor shaft, said head including a plurality of spaced elements, and a plurality of members loosely supported by said elements, and means whereby the adjustment of said base may be effected to cause 35 said members to intermittently strike the selvage of said fabric upon rotation of said shaft and head.
- In testimony whereof, I have signed my name in the presence of two subscribing witnesses.

MARK A. REPLOGLE.
